(57) **CLAIM**

The ornamental design for a one-handed fire starter, as shown and described.

DESCRIPTION

FIG. 1 is perspective view of a one-handed fire starter showing our new design;

FIG. 2 is a top plan view thereof;

FIG. 3 is a right side view thereof;

FIG. 4 is a left side view thereof;

FIG. 5 is a front view thereof; and,

FIG. 6 is a bottom plan view thereof.

The broken lines in the drawings are included for the purpose of illustration and form no part of the claimed design.
